MICHAEL GOGGINS, OF BOSWELL, NEW MEXICO

HAY BALER AND LOADER

Application filed October 13, 1928. Serial No. 312,236

lar sprocket wheel 26 is secured on the end of the transmission shaft 22, a sprocket chain 27 being trained around these sprockets. A spiral gear 28 is secured to the transmission shaft at a point near the rear wheels 4 and meshes with the spiral gear 29 on a transverse drive shaft 30 journaled in bearings 31 depended from the lower frame rails 2. Large gears 32 are secured within, or to one side of, the wheels 4 and pinions 33 on the ends of the shaft 30 mesh therewith. Thus it will be apparent that the machine may be driven over the ground by the engine 11 and it will be understood that any conventional form of speed shifting and control means may be used upon the engine, and no specific form being here shown.

A transverse shaft 34 is journaled in bearings 35 upon the top rails 3 extending outwardly at one end and a large gear 36 is secured thereon in mesh with the pinion 17 on the drive shaft 12. Short stub shafts 37 are journaled in side plates 38 and large drive gears 39 are mounted upon the inwardly turned extended ends thereof. Pinions 40 upon the shaft 34 mesh with the gears 39 so that the latter will be rotated by the motor 11 as will be understood.

A plunger or beater 41 is reciprocatingly mounted in the frame 1, the same comprising the head 42, sides 43 and slotted bottom 44. This plunger 41 has transverse rollers 45 journaled in the said slots in the bottom 44 which will roll along the horizontal webs of the angle irons forming the lower frame rails 2. A connecting rod 46 is pivotally mounted in the beater 41 on a pin 47 and is also pivotally mounted at its opposite end between the gears 39 on a pin 48 supported eccentrically upon the said gears, the ends of the said connecting rod being laterally enlarged as shown for this purpose. It will now be understood that as the gears 39 are rotated by the means hereinbefore set forth, the plunger 41 will be caused to reciprocate within the frame 1 and so will press or bale hay forced therein by a means to be set forth.

The separating block holder or slide 49 of the shape clearly shown in Figure 16 has a slideway formed between the ends 50, the back 51 and the webs 52. This block holder 49 is pivotally mounted between the top frame rails 3 by short pivot pins 53 passed through the apertures 54. A gear 55 is secured upon one of the pivot pins 53 and a gear 56 with a handle 57 on a pivot pin 58 meshes therewith and by raising or lowering the handle 57 the block holder 49 may be raised into the vertical or operative position shown or lowered so that it will lie flat upon the frame 1. A block operating mechanism is provided comprising the arm 59, the forwardly disposed end of which is bifurcated and the arms pivoted in brackets 60 upon the top frame rails 3. A link 61 is pivotally connected by one end at

62 to a medial point of the arm 59 and is similarly connected at its opposite end to an ear or lug 63 formed upon the upper side of the connecting rod 46. A rectangular block hammer or striker 64 is secured upon the free end of the arm 59. A separating block 65 is provided to separate the bales one from another as they are formed by the means hereinbefore set forth, and the same is of the usual form having grooves 66 through which the wires (not shown) may be passed when wiring or tying the bales. In the use of the bale separating elements the block holder or slide 49 is raised to the vertical position when enough hay has been pressed to form one bale and a separating block such as described is inserted therein. The arm 59 due to its connection with the connecting rod 46 is caused to move vertically up and down and thus the block striker 64 will impinge the upper edge of the block 65 forcing the same downward into the baling chamber and separating the hay therein as will be understood. When the block holder 49 is not in use it is adapted to lie flat upon the frame and in this position the striker 64 will clear the same having no effect thereon. It will be understood that a block may be inserted in the holder and forced downward by hand to form an end piece or brace against which the first bale may be pressed. The bales are tied in the usual manner, suitable platforms 67 being secured on brackets 68 at the sides of the frame upon which the tiers may stand. The rear end of the frame may be constricted, when necessary to hold the bales within the frame, or to cause the same to be pressed more tightly, by means of the handwheels 71 which threadedly engage the ends of the bolts 72. These bolts 72 are secured at their lower ends to a cross-piece 73 and small lugs 74 are loosely placed upon the upper ends as shown bearing upon the upper frame rails 3. By this means the spaced lower frame rails 2 and the upper frame rails 3 may be drawn together, it being understood that the side plates are omitted adjacent the rear of the frame.

A rectangular table 75 is loosely mounted upon the lower rail 2 at a medial point of the frame and the free margin thereof is provided with a supporting frame comprising the depending vertical members 76 and the horizontal member 77. A side brace member 78 is mounted by one end upon the axle 5 and extends forwardly and outwardly and is secured to the lower ends of the vertical frame members 76. An adjusting rod 79 has its upper end 80 threaded and passed loosely through sockets 81 formed in both the horizontal member 77 and the brace 78. A bevelled pinion 82 threadedly engages the threaded end 80 of the adjusting rod 79. A small castor wheel 83 has its axle journaled in a bearing 84 on the foot 85 formed at the lower end of the rod 79.

A similar wheel 86 is journaled upon a stub shaft extended from a hanger 87 depended from the inner margin of the table 75 as shown in Figure 3. Thus the table 75 is susceptible of vertical adjustment and is flexibly supported to overcome inequalities of the ground over which the machine travels and by meshing a beveled gear (not shown) with the beveled pinion 82 and extending the shaft there-
5 of adjacent the driver's seat the wheel 83 may be adjusted by the driver, such steering devices are conventional and no invention is claimed in respect of same as here applied.

As shown in Figure 3 a bearing hanger 88 is depended from the inner margin of the table 75 adjacent the front thereof and a bearing aperture 89 is formed in the brace 78 in alignment therewith. A rake shaft 90 is journaled through the bearing hanger 88 and the aperture 89 and is provided at its inner end with an internally toothed bevel gear 91. A bearing arm 92 is secured on, or formed integrally with, the bearing hanger 88 and a bearing bracket or ranger 93 is depended from the bottom plate 69 of the frame 1. A shaft 94 with a universal joint 95 is journaled in the said arm 92 and hanger 93 and has a beveled gear 96 on one end meshing with the gear 91 on the rake shaft 90, the said shaft 20 also having a beveled pinion 97 at its opposite end. Bearings 98 are provided on the sides of both the upper and lower frame rails 3 and 2 and a shaft 99 is journaled vertically therethrough, the same having at its lower 25 end the large bevel gear 100 with which the beveled pinion 97 meshes. A beveled pinion 101 on the end of the sleeve 24 meshes with the said gear 100 and motion is transmitted to the sleeve 24 from the jack shaft 20 by means 30 of sprocket 102 and a sprocket chain 103 substantially as hereinbefore set forth for the transmission shaft 22. The large beveled gear 100 is thus rotated and the rake shaft 90 will be turned in the direction indicated by 35 the arrow by means of the shaft 94 and its associated gears.

A revolving rake 104 is secured upon the rake shaft 90, the same comprising the side frame wheels 105 and 106 secured upon the 40 said rake shaft in spaced relation. Rods 107 are journaled through the rims 108 of the said wheels 105 and 106 and extend therethrough at their outer ends for a purpose to be described. Rake teeth 109 are secured upon the 45 rods 107 at equally spaced intervals and it will be understood that the said teeth may be spring set in any conventional manner as by spring set rule joints (not shown) so as to prevent breakage when striking obstructions. The forward margin of the table 75 is arcuately curved in a downward direction and is provided with slots 110 through which the rake teeth 109 are adapted to pass 50 as they revolve. To allow the said rake teeth 109 to clear the table 75 a cam 111 of the shape

shown in Figures 1 and 7 is secured by bolts 112 to the vertical frame member 76. The said outer extended ends of the rods 107 are provided with angularly bent arms 113 upon the ends of which are rotatably mounted the 70 rollers 114 adapted to bear against the face of the cam 111. In this manner when the rake teeth 109 are in the lower portion of their travel they are held rigidly extended but as they enter the slots 110 in the table 75 75 the rollers 114 disengage the cam 111 and the teeth and rods 107 turn freely so that the said teeth will clear the table.

The hay thus deposited on the table 75 is fed into the bailing chamber by a fork 115 80 adapted to enter the feed opening 116 in the side plate 70. A slide rail 117 is mounted on the table 75 at the rear margin thereof by standards 118 and the said rail 117 is T-shaped in cross section as shown. A slide 85 block 119 is slidably mounted on the rail 117 and has at its rearwardly disposed side a vertical bore or bearing aperture 120. The fork 115 comprises a crank 121 as shown in Figure 8, the said crank being formed of a 90 hub or shaft 122 rotatably seated through the bearing aperture 120 and the upper and lower arms 123 and 124 secured at one end to hub 122 and held in spaced relationship above and below the slide block 119. A vertical shaft 95 125 is secured to the free end of the upper arm 123 and a short stub shaft 126 is secured to the lower arm 124. The fork tines 127 are secured at a medial point to the shafts 125 and 126 adjacent the upper and lower arms 100 123 and 124 and have the bifurcatd hay engaging ends 128. The shaft 99 is extended above the top of the frame 1 and provided with a rigidly fastened crank arm 129 at its upper end, the said crank arm having at its 105 outer end the short stub pivot shaft 130. A sprocket 131 is secured upon the upper end of the shaft 125 on the crank arm 123 and a similar sprocket 132 is secured upon the stub pivot shaft 130, a sprocket chain 133 being 110 trained around these sprockets as shown. A connecting link 134 is rotatably mounted by its ends on the said shaft 125 and pivot shaft 130.

It will now be understood that the rotation of the shaft 99 through the pinion 101 and gear 100 as hereinbefore set forth will cause the crank arm 129 to rotate. This arm through the link 134 will cause the crank 121 to turn and at the same time will slide the 120 entire fork assembly 115 on the T rail 117 since the said arm 129 has a much greater throw than the arms 123 of the crank 121. By means of the sprockets 131 and 132 and the sprocket chain 133 the crank 121 is caused to 125 rotate completely around on its hub 122 and this sprocket and chain connection is so adjusted that when the fork is on the "in" stroke, that is, feeding hay inward from the table 75 into the baling chamber, the bifur- 130

cated ends 128 of the tines 127 will swing or sweep forwardly and inwardly to the frame over the said table. The said tines are adapted to swing somewhat within the baling chamber on their "in" stroke as shown in Figure 4 and it will be understood that the fork 115 and plunger 42 must be arranged or timed so that when the said fork is sweeping inwardly to the baling chamber, the plunger 42 must be drawing forward in the frame 1 on its inoperative stroke and this relationship is also clearly shown in Figure 4. On the out or inoperative stroke of the fork the said bifurcated ends 128 of the tines 127 will swing to the rear behind the table thus clearing the hay accumulated on the table as the fork as in the baling chamber. Thus the fork makes a complete revolution during the in and out strokes and at the same time the entire assembly is slid inwardly and outwardly on the T rail 117. In Figures 1, 2 and 3 the fork is shown just starting its "in" or feed stroke and in Figure 4 the same is shown as its feed stroke is completed and as it starts swinging outward on its "out" stroke. This construction provides a very efficient means for forcing hay into the baling chamber as will be readily appreciated.

In order to retain the hay in the baling chamber as it is being baled, I provide a door denoted generally at 135 adapted to close the feed opening 116 and it is obvious that this door must operate in connection with the fork 115, that is, when the fork is feeding hay into the baling chamber the said door must be open and as the fork is drawing outward on its inoperative stroke the said door must close. Guideways 136 are secured to the upper and lower frame rails extending along above and below the feed opening 116 and to the rear thereof as shown, the said guideways being disposed with their troughs reversed or facing each other as will be understood. The door 135 is provided at each end with rollers 137 rotatably mounted in brackets 138 and these rollers are adapted to roll in the guideways 136 in such manner that the door 135 may be readily moved to and fro to open or close the feed opening 116. A large medial slot 139 is provided in the door 135 to clear the T rail 117 and spaced from either side thereof are narrow slots 140 to clear the fork tines 127, these slots 139 and 140 extending rearwardly in the door and terminating short of the rear edge thereof as shown. A retractile coil spring 141 is stretched between the forward margin of the feed opening 116 and a medial point of the door 135, the said spring being positioned near the upper margin of the said door and serving to normally retain the same in the forward or closed position. A lug or catch 142 is secured to the upper forward margin of the door 135 and projects inwardly into the baling chamber, a slot 143 being provided in the frame side

plate 70 to allow for the movement backwardly and forwardly thereof. It will be understood that as the plunger 41 moves into the baling chamber on its pressure stroke, the head 42 thereof will strike the lug 142 forcing the door 135 open. In order to retain the said door in the open position as the plunger is moving out of the baling chamber and while hay is being forced through the opening 116 I provide a catch lever 144 pivoted at 145 to the upper frame rail 3 and being of sufficient length to engage the forward margin of the door when the same is open. An elongated operating rod 146 is loosely attached at 147 to a medial point of the catch lever 144 and extends forwardly through a bracket 148 secured to the said upper frame rail 3 and terminates in a trigger 149. A coil spring 150 is stretched between the trigger 149 and the bracket 148 serving to normally swing the catch lever 144 rearwardly against the door 135, a stop 151 limiting this motion. As the plunger 41 reaches the end of its inoperative stroke drawing out of the baling chamber the side 43 thereof will strike the trigger 149 pulling the rod 146 and catch lever 144 forward releasing the door 135, the coil spring 141 then pulling the said door forward into its closed position, it being understood that the timing between the fork and plunger is such that the hay is fed into the baling chamber while the plunger is withdrawn therefrom. In order to allow the door 135 to pass the catch lever 144, as it opens the latter is provided with a spring set rule joint 152. A slot 153 in the side 43 of the plunger allows the same to complete its inoperative stroke before it actuates the trigger 149 to close the feed opening door as will be understood.

Dogs 154 are pivoted at 155 in slots 156 in the side plates 70 on either side of the frame to the rear of the feed opening 116, their purpose being to retain the hay in its pressed condition as the plunger recedes to press another portion of hay. These dogs 154 are spring set to normally swing into the baling chamber a sufficient distance so that the hooks 157 thereof will engage the hay. The plunger 41 when pressing the hay strikes the arcuate outer faces 158 of the said dogs 154 forcing them outward so that the said plunger may pass as shown in the dotted lines in Figure 10.

An elevator denoted generally at 159 is provided upon the rear of the frame 1 to deliver the bales clear of the machine. A table 160 is secured by bolts 161 to the lower frame rails 2 and the same is provided with spaced upstanding lugs 162. An elevator frame 163, U-shaped in cross section, and having aligned bearing apertures 164 at either end of its side portions is mounted between the lugs 162 and extends laterally and angularly upward from the frame as shown in Figure 6. Toothed elevator rollers 165 are rigidly mounted on 166

shafts 166 journaled in the bearing apertures 164, the lower shaft being extended outwardly through the lugs 162 serving as a pivot for the frame 163 as shown at 167 and provided at its forward end with a sprocket 168. A similar sprocket 169 is provided on the rear end of the transmission shaft 22 and a sprocket chain 170 is trained around these sprockets so that rotary motion will be transmitted to the lower elevator roller 165 as will be understood. An elevator belt 171 of suitable material such as canvas is stretched over the rollers 165, the inner surface of the belt being provided with equally spaced transverse slats 172 to engage the teeth upon the wheels. Small spikes 173 are provided on the belt in order to obtain a firm grip upon the bales when elevating the same. An adjusting rod 174 is loosely secured to the upper end of the elevator frame 163 and has its opposite end threaded and loosely passed through a standard 175 upon the frame 1. A sprocket 176 threadedly engages the threaded end of the rod 174 and it will be understood that by turning the said sprocket 176 the rod 174 may be moved outwardly or drawn inwardly, this action varying the angle of the elevator 159 as will be understood. A hand wheel 177 with sprocket 178 is provided and by training a sprocket chain 179 over the sprockets 176 and 178 the angle of the elevator may be varied at will by the machine operator.

The tiers when a bale is tied may pull the same out the open rear end of the frame onto the table 160. The bale may then be placed upon the elevator 159 and delivered to a wagon or truck driven beside the baler. The operator by means of the handwheel 177 may vary the height of the outer end of the elevator at will to deliver the bales to the wagon in any position.

From the foregoing it is obvious that I provide a machine which is positive and efficient in operation and which completely eliminates the raking up and loading of hay in the field and then transporting the same to the baling machine.

While I have herein set forth a certain preferred embodiment of my invention it is understood that I may vary from the same in minor structural details, so as best to construct a practical device, not departing from the spirit of the invention and within the scope of the appended claims.

55 I claim:

1. In a device of the kind described, a frame including a baling chamber having a feed opening, a plunger mounted for reciprocation in the baling chamber, a door mounted on the frame and adapted to normally close the said feed opening, and cooperating means upon the door and plunger whereby the door is opened by the inward movement of the plunger into the baling chamber and is locked in that position until

the completion of the outward movement of the plunger.

2. In a device of the kind described, a frame including a baling chamber, having a feed opening, a plunger mounted for reciprocation in the baling chamber, a door slidably mounted on the frame along side the feed opening, a retractile coil spring stretched between the door and frame to normally hold the said door closed over the feed opening, a catch extended inward from the door into the path of the plunger whereby the door will be forced open as the plunger moves inward into the baling chamber, and means whereby the said door is retained in the open position until the plunger reaches the end of its outer stroke.

3. In a device of the kind described, a frame including a baling chamber having a feed opening in its side, a plunger mounted for reciprocation into and out of the baling chamber, a door slidably mounted on the frame alongside the feed opening, a retractile coil spring stretched between the door and frame to normally hold said door in closed position over the feed opening, a catch extended inward from the door into the path of the plunger whereby the door is forced open as the plunger moves into the baling chamber, a catch lever pivoted to the frame and adapted to engage the margin of the door and hold the same in its opened position, an operating rod pivotally connected to the catch lever and extending in the frame alongside the baling chamber, a trigger on the end of the operating rod extended into the path of the plunger for engagement thereby as the same moves outward from the baling chamber, and a retractile coil spring stretched between the trigger and frame to normally hold the catch lever in engagement with the margin of the door.

4. In a device of the kind described, a frame including a baling chamber having a feed opening, and a door slidably mounted on the frame to open and close the said feed opening, a table supported on the frame alongside the feed opening, and a fork operatively mounted over the said table to sweep inward through the feed opening in timed relation with the opening of the said door.

5. In a device of the kind described, a frame including a baling chamber having a feed opening, a plunger mounted for reciprocation in the baling chamber, and a door slidably mounted over the feed opening and operated to open and close the same by the reciprocation of the plunger, a table mounted on the frame alongside the feed opening, a slide rail mounted on the table, a slide block slidably mounted on the slide rail, a fork crank including a hub journaled in the slide block, and forks secured to the said fork crank and adapted to sweep over the said
